UNITED STATES PATENT OFFICE.

HUGO DORNSEIF, OF RADEVORMWALD, GERMANY.

MANUFACTURE OF SKATE BLADES WITH THICKENED EDGES.

Application filed October 2, 1925, Serial No. 60,116, and in Germany October 2, 1924.

It has already been proposed to manufacture skate-blades with a thickened edge by stamping out of sheet or band steel a blank or work-piece of the contour of the skate and then upsetting this work-piece on edge in the cold in order to form a rib on each side of the blade-edge. This known process has not been proved practicable in the first place because upsetting the blade simultaneously throughout its entire length requires exceedingly high pressure, which can be produced only with presses of very considerable dimensions, and in the second place because the edge of the work-piece to be upset tends to bend under the pressure of the upsetting stamp towards that side whereon the burr was formed when the work-piece was stamped. In consequence, the material worked on, when it is upset, flows first of all only toward one side and it must then be forced towards the other side, whereby the structure of the material is detrimentally affected and a faulty article is produced.

Now the object of the present invention is to render this known process practicable by requiring for carrying out the process only a comparatively small pressure and accordingly a small machine, and at the same time obtaining work-pieces which are thoroughly free from fault.

According to the present invention the skate-blade is no longer upset simultaneously throughout its entire length but is upset progressively step by step from one end to the other in such a manner that, at each step, only a fraction of the total length of the skate-blade is subjected to the upsetting pressure. Moreover, in order to avoid bending the edge towards one side and to obtain a uniform spreading, towards both sides, of the material to be upset the outward flow of the material is limited at both sides to correspond to the desired cross-sectional shape of the edge, while simultaneously those portions of the non-upset and already upset edge which are adjacent to the place being worked are supported on both sides. This limitation of the material and simultaneous guidance of adjacent portions of the edge are brought about in the simplest manner by forming in the stamp a groove which serves as upsetting matrix, which groove, at that portion thereof which is behind in the direction of ad-

vance of the work-piece, has a width corresponding to the thickness of the non-upset work-piece, while at its middle portion it widens gradually to the full width of the thickened edge of the skate, its depth simultaneously gradually diminishing, and then it continues with a constant width. In order to facilitate the reshaping work the upsetting stamp moves preferably not at right angles to the edge of the skate-blade but at such an angle thereto that the centre line of the upsetting stamp about bisects the angle between said edge and the slanting face connecting the non-upset to the upset portion of the edge. As experiments have proved, it is possible by the new process to upset the edge of the skate-blade with a minimum consumption of power while at the same time work-pieces which are quite faultless are obtained.

The new process may be carried out on a simple and light machine comprising a press-slide or hammer movable up and down. It is most advantageous to employ a mechanical hammer constructed in the manner of a file-cutting machine and provided with a work-piece slide adjustable on an inclined plane.

The accompanying drawings illustrate in Figs. 1-10 thereof a first example of the new process in connection with tools as well as a machine for carrying out said process. Figs. 11 to 19, inclusive, cover a modification of my machine and will be described in the latter part of the specification.

Of these figures:-

Fig. 1 shows the upsetting stamp, the work-piece and the jaws containing the latter, partly in side elevation and partly in vertical section,

Fig. 2 is an elevation of the stamp as viewed from the right of Fig. 1,

Fig. 3 a bottom plan view of the upsetting stamp,

Fig. 4 a section on the line A—A in Fig. 1,

Fig. 5 a section on the line B—B in Fig. 1,

Fig. 6 a section on the line C—C in Fig. 1,

Fig. 7 a side elevation of the work-piece partly upset and partly not upset,

Fig. 8 a top view of the same,

Fig. 9 a section on the line D—D in Fig. 7, and

110

Fig. 10 a front elevation of the machine for carrying out the new process.

In the new process, as heretofore a work-piece *a* of the contour of the skate-blade is first stamped out of sheet or band steel. This work-piece of which, since it is known, only a portion is shown in the drawing is as usual held gripped in an upright position between two clamping jaws *b*, *b* in such manner that the edge to be upset projects upwardly above the jaws. The two clamping jaws *b*, *b*, are mounted on a slide *c* which is fitted so as to be longitudinally displaceable on the inclined bed *d* of the spring-hammer (Fig. 10) and can be moved step by step by suitable feeding means in the direction of the arrow *x*. On the hammer *f* which is movable up and down above the bed is secured an upsetting stamp *g* wherein, in its lower side which is slanted off correspondingly to the inclination of the bed *d*, a channel *h* is formed which serves as upsetting matrix, and which preferably has a wedge-shaped cross section for the purpose of readily applying and raising the stamp to and from the work-piece. The bottom face of the channel has, in the portion 1 which is behind in the direction of advance of the slide *c*, the same width as the upper edge of the non-upset portion *a*¹ of the work-piece. At the middle portion 2 of its length the channel *h* widens gradually to the full width of the thickened, that is, upset edge *a*³ while simultaneously the depth of the channel 35 gradually diminishes. Thereupon the channel at its portion 3 continues at the same depth and width. If desired however, as illustrated in Fig. 4, the channel may be again widened at its end 4 which is in front 40 in the direction of advance in order that the work-piece may here be free from the sidewalls of the channel.

The work-piece is advanced intermittently or step by step below the hammer *f* in the direction of the arrow *x* by means of the slide *c*, while said hammer is lifted in regular succession by means of a cam-disc and then given a blow-like movement downwards by means of the spring *i*. The stroke of the hammer is so limited that it can go no further downwards as soon as the bottom faces of the narrow and wide portions 1 and 3 respectively of the channel *h* formed in the stamp come in contact with the upper edge of non-upset and already upset portions *a*¹ and *a*³ respectively of the work-piece *a*. On the latter portions, therefore, no substantial pressure is exerted, but the side walls of the channel mainly coact with them so that the work-piece is supported on both sides by the side-walls of the channel and consequently preserved from bending over to one side. On the other hand an upsetting pressure is exerted on that portion *a*² 60 of the work-piece, that is, the portion im-

mediately in front of and behind the section line B—B in Fig. 1, which is at the moment facing the portion 2 connecting the narrow and deep to the wide and shallow portions of the channel *h*, whereby the material being worked is spread out towards both sides as far as the side walls of the channel permit. Before each fresh blow of the hammer the work-piece is advanced a small distance in the direction of the widening of the channel so that that portion of the work-piece which was incompletely upset at the first blow arrives at a wider portion of the channel and consequently can flow outwardly to a greater width, and so on, while at each advance a portion of the work-piece which had hitherto not been upset is simultaneously subjected to a first upsetting pressure. The distance advanced at each step may be made so small that the shaping of a given length of the blade-edge, e. g. of a portion of the length of the connecting portion 2 of the channel *h*, may be effected in a very large number of stages, and therefore quite gradually. Moreover, since on the one hand outward flow of the material towards both sides is limited and on the other hand during the upsetting movement the work-piece, both in front of and behind the place being upset, has its upper edge supported on both sides by the walls of the portions 1 and 3, bending of the work-piece and spreading of the same only towards one side are entirely avoided. The upset material always spreads out uniformly towards both sides so that no destruction of its structure leading to a faulty product can occur. The intermittent advance of the slide *c* is continued until the entire work-piece has passed below the hammer *f* and the blade-edge has been thereby upset throughout its entire length.

The inclination of the bed *d* is preferably so chosen that the vertical centre line of the upsetting stamp about bisects the angle *x* between the upper edge of the already upset portion *a*³ of the blade of the skate and the inclined upper edge of the portion *a*² being shaped. The pressure of the stamp *g* is thereby given a direction specially advantageous for the work of shaping, while at the same time no substantial lateral pressures due to the resistance of the material are produced on the stamp. If desired the work-piece might have a different inclination to suit the form of the stamp so that the direction of pressure might be more or less at right angles to the upper edge of the portion *a*² being shaped.

As seen from the drawing, the bottom face of the channel formed in the upsetting stamp may be curved in the transverse direction in order to provide the edge of the skate at once with a groove which is otherwise produced by grinding. The said face may how-

ever be flat when the running edge is to have no groove or to be provided with one by grinding.

Although in the example a skate with a straight edge is shown, obviously the new process may be employed for the manufacture of skate-blades with bowed or curved edges. In this case the slide *c* carrying the work-piece would advantageously be guided 10 on a bed of correspondingly curved upper face or made capable of being swung about the centre of the arc formed by the edge.

In the above described apparatus for carrying out the new process the walls serving 15 for laterally supporting the portion at the moment being upset and these portions of the blade-edge which are immediately adjacent to this are located wholly on the upsetting stamp. The latter consequently 20 braces both the non-upset and the finished portion of the edge, which requires that in the cross-sectional formation of the finished edge regard must be paid to the raising of the stamp from the work-piece, by making 25 the cross-section of the thickened edge somewhat narrower towards the bottom since it is necessary for the repeated raising of the upsetting stamp from the work-piece that the side-walls of the channel in the stamp 30 should converge upwardly.

In order to have free choice of the cross-sectional shape of the thickened edge it is recommended that the apparatus be so designed that the upsetting stamp contains in 35 addition to the pressure face only the lateral supporting faces for the non-upset and the at-first incompletely upset portions of the work-piece, whereas the lateral supporting faces for the finally upset portion are located 40 on the jaws which clamp the work-piece. With this distribution of the supporting faces, in the cross-sectional formation of the thickened edge no regard need be paid to the raising of the stamp from the work-piece. 45 The side-faces for laterally supporting the finally upset edge may either be parallel or converge downwardly because they no longer move up and down with the stamp. Consequently it is possible to give 50 to the thickened edge a cross-section which is constant throughout its entire height or even becomes wider towards the bottom. This shape of cross section is advantageous 55 inasmuch as the side-faces of the edge then form with the preferably concave blade-face as acute an angle as possible, so that the edges of the blade-face cut into the ice and prevent lateral movements, that is, slipping, 60 of the skate.

The arrangement of a portion of the lateral supporting faces for the blade-edge on the clamping jaws requires that there must be formed in them a channel corresponding to the profile of said edge. There- 65 by difficulty arises in bringing again into

the prescribed form the operative faces of the clamping jaws which become bent in consequence of distortion during hardening. Whereas in the case of the clamping jaws of the apparatus according to Figs. 1-10 the 70 clamping faces lying in one plane can be comparatively easily reground, regrinding of the walls of the profiled channel in the clamping jaws is very tedious and slow, if not impossible. Straightening the jaws 75 under a press in a single operation does not come into consideration because after removal of the pressure the jaws return to their curved condition in consequence of their elasticity. Now in order to avoid the 80 tedious and slow finishing work on the hardened clamping jaws by grinding, according to the present invention, when a work-piece is secured, the clamping jaws are to be so tightly clasped between a wall of the slide 85 containing them and a key capable of displacement parallel to the jaws and extending throughout their entire operative length that they are straightened by the pressure of the key and consequently made perfectly plane. 90 The difficulty of being able to tighten up the key sufficiently firmly and release it is met by providing for tightening and releasing the key two spring-hammers at the ends 95 of the gripping device, which hammers comprise hammer-spindles guided parallel to the key. The spring-hammers not only permit the key to be tightened as firmly as desired but have also the advantage that the tightening and release of the key and consequently 100 the exchange of the work-pieces can be effected in an exceedingly short time.

Figs. 11-19 of the accompanying drawings show by way of example this modified apparatus, of which figures:— 105

Fig. 11 shows the upsetting stamp, work-piece and clamping jaws securing the latter, partly in side elevation and partly in vertical longitudinal section,

Fig. 12 is a bottom plan view of the upsetting stamp,

Fig. 13 a top plan view of the clamping jaws,

Figs. 14-17 are four vertical sections respectively on the lines 4-4, 5-5, 6-6 and 115 7-7 in Fig. 11,

Fig. 18 is a side elevation of the slide containing the clamping jaws for the work-piece, and

Fig. 19 a top plan view of the same.

The two clamping jaws *b*, *b* which receive between themselves the upright skate-blade *a* are again mounted on a slide *c* which is so mounted as to be longitudinally displaceable 125 in the inclined bed of a spring-hammer according to Fig. 10 and can be intermittently advanced in the direction of the arrow *x* by means of suitable feed mechanism. The upsetting stamp *g* is mounted on a hammer movable up and down above the bed and is 130

again slanted off on its lower side correspondingly to the inclination of the machine-bed.

In the lower side of the upsetting stamp g is formed a channel h^1 , the lateral walls of which converge upwardly. In contradistinction to the upsetting stamp in the example according to Figs. 1-10, this channel does not extend over the entire bottom face of the stamp but only about over that half of said face which is behind in the direction of advance of the work-piece (arrow x). The said channel has at its rear a width corresponding to the thickness of the crude work-piece while towards the middle of the stamp it gradually widens while its depth simultaneously diminishes. Only about half of the pressure face of the stamp is therefore formed by the bottom of the channel h^1 , while its remaining portion h^1 , which is in front in the direction of advance of the work-piece, is located directly on the bottom face of the stamp g . The portion h^2 either is flush with the bottom face of the stamp—namely, in the case of a plane pressure face—or projects from the bottom face of the stamp, as in the case of the curved pressure face shown.

Whereas in the apparatus shown in Figs. 1-10 the clamping jaws b have on their opposite sides simply plane clamping faces throughout which leave between themselves a gap for receiving that upper portion of the blade which remains unchanged, in the example according to Figs. 11-19 this gap is widened in the upper portion of the jaw-faces to form a channel k having the same width and cross-sectional shape as the thickened edge to be produced.

Upsetting of that portion of the blade which rises freely from the clamping jaws b is effected intermittently as above described, the upsetting stamp g falling on the work-piece and being again raised in regular succession, and the slide c with the two clamping jaws b containing the work-piece being advanced at each lift of the stamp g a predetermined distance in the direction of the arrow x . Similarly as in the example, according to Figs. 1-10 both the portion at the moment being reshaped and these portions immediately adjacent to the reshaping place are supported laterally by the walls of the channels h^1 and k so that both bending and unilateral spreading of the blade-material are avoided.

In contradistinction to the first example however the lateral supporting faces are no longer provided wholly in the upsetting stamp g but in part in the clamping jaws b , in fact, in the upsetting stamp are arranged only those lateral faces which support the non-upset portion of the blade-edge and the incompletely upset portion, which the supporting faces for the finally upset portion

of the edge are located in the clamping jaws b . These supporting faces no longer share the up-and-down motion of the stamp g so that they may be either vertical or downwardly convergent, whereby the blade-edge 70 may be provided either with parallel faces or with downwardly convergent lateral faces forming with the blade-face an acute angle.

The two clamping jaws (see Figs. 18 and 19) are arranged in a recess m in the top 75 of the slide c which recess contains also a key n , which is displaceable longitudinally with respect to the jaws and extends over the entire operative length of the latter and which serves to press the jaws together. For tightening and releasing this key there are provided according to the present invention two spring-hammers mounted at the ends of the slide c . Each of the two spring-hammers comprises a hammer-spindle o which is guided parallel to the key n and is influenced by a powerful spring P pressing against the key and which carries a tappet-arm q . To coact with the arm q is provided a cam r mounted on a shaft s transverse to the spindle O . When the shaft s is rotated in the direction of the arrow y the cam r presses the spindle o outwardly 80 against the tension of the spring P at regular intervals, whereupon the spring each 85 time returns the spindle inwardly with a blow-like movement. One or the other resilient hammer is actuated according to whether the key is to be tightened or released, which may be brought about by the aid of a belt and fast and loose pulleys mounted on the shaft s or in any other suitable manner. Owing to the arrangement of the spring-hammers the key n may be tightened 90 so firmly that the two clamping jaws 100 which as is well known become distorted, and thereby bent, in the hardening may be perfectly straightened when a work-piece is gripped. Consequently the tedious and slow work of finishing the operative faces of the hardening jaws is dispensed with.

What I claim is:—

1. In a machine for cold swaging a skate blank for the production thereon of a runner edge of widened cross-section with respect to the thickness of the blank body, a support for the blank, a die of a length for swaging a comparatively small portion of the edge of the blank compared with its length on each swaging action, said die having a channeled swaging face provided with an inclined central swaging surface, a shallow front portion to embrace and hold the unswaged edge of the blank in advance of the swaging point from lateral deflection, and a relatively deeper and flaring rear portion to embrace and hold the swaged portion of the blank in rear of the swaging point from lateral deflection, means for reciprocating 115 said die to act on successive short portions 120 of the edge, and a support for the blank 125 which supports the blank in rear of the swaging point from lateral deflection, and a relatively deeper and flaring rear portion to embrace and hold the swaged portion of the blank in rear of the swaging point from lateral deflection, means for reciprocating 130 said die to act on successive short portions

of the blank as presented thereto by intermittent relative movements between the blank and die, and means for shifting the support and blank relative to the die to present new portions of the blank to the action of the die successively from end to end of the blank.

2. In a machine for the manufacture of skate-blades with a thickened running edge, the combination of a support for holding a blank stamped out with the contour of a skate-blade, a reciprocatory die for upsetting the running edge of the blank at short length stages progressively by step by step swaging actions from end to end of the blank, means for producing relative motion between the die and support for successively bringing different portions of the blank into the plane of working motion of the die, and means for adjusting the support at an inclination to the longitudinal direction of the running edge of the blade.

3. In a machine according to claim 1, a die (as *g*) formed on its bottom with a channel having a rear portion (1) of a width corresponding to the thickness of the blank, a middle portion (2) which gradually widens to the width of the intended thickened running edge while simultaneously gradually decreasing in depth in a forward direction, and a front portion (3) of a width and depth corresponding to the thickness of the intended thickened running edge to be formed upon the blank.

4. In a machine according to claim 1, the arrangement of the work face of the upsetting hammer and the edge of the blank at such an angle to each other that the center line of the upsetting hammer bisects the angle between the upset running edge and the face of the blank being shaped.

5. In a machine according to claim 1, an upsetting hammer having an offsetting face, faces for limiting the outward flow of the upset portion of the blank at both sides of the blank during the upsetting action, and faces for supporting the non-upset portion of the blank, and clamping jaws having supporting faces for the finally upset portion of the running edge of the blank.

6. In a machine according to claim 1, an upsetting hammer formed with a channel having an offsetting portion, said channel being narrow and deep behind, but wide and shallow in front of said offsetting portion, said channel terminating at the end of said wide and shallow portion flush with the bottom face of the hammer, and relatively adjustable clamping jaws formed with a groove corresponding to the finished running edge of the skate-blade.

7. In a machine according to claim 1, a stationary and a movable clamping jaw for

securing the blank, a key longitudinally displaceable with respect to the jaws, and two spring-actuated displacing hammers arranged at the end of the clamping device for action on said key.

8. The method of cold swaging a skate blank for the production thereon of a runner edge of widened cross-section with respect to the thickness of the blade body, which consists in upsetting the edge of the blank, starting at one end of the blank, by successive strokes of a die at successive short length zones, stages progressively from such end of the blank toward the opposite end of the blank so as to displace the metal laterally at each zone stage relatively to the body of the blank to equal degrees on both sides of the blank to thereby form a widened edge of a determined cross-section while limiting the outward lateral flow of the metal at both sides of blank at each upsetting stage and supporting the blank against lateral deflection in adjacent zones lying in front and rear of such stage, and relatively shifting the blank and die intermittently to bring different portions of the edge of the blank successively into position for the stage by stage upsetting action.

9. In a cold swaging machine for the manufacture of skate blades with a thickened running edge, means for holding a skate blank, a die having an acting surface for swaging a comparatively small portion of the edge of the blank with respect to its length on each complete swaging action of said die and channeled portions to embrace the blank in the region of its edge at and in front and rear of the swaging point to limit the lateral displacement of the metal and to support the blank against lateral deflection, and means for producing a relative feed motion between the blank and die lengthwise of the former for successively presenting portions of the edge of the blank to the action of the die from end to end of the blank.

10. In a machine for cold swaging a skate blank for the production of a runner edge upon the blank of widened cross-section with respect to the blank, a hammer having a channeled die face to embrace the edge of the blank on each working motion thereof, said channel being continuous from end to end of said die face and having a front portion of minimum width and maximum depth, a rear portion of maximum width and less depth, and an intermediate portion of increasing width from front to rear and of varying depth, the wall of the intermediate portion of the channel forming a swaging surface inclining at an angle between the top walls of said front and rear portions.

In testimony whereof I affix my signature.
HUGO DORNSEIF.
